UNITED STATES PATENT OFFICE

JOSIAH B. GATHRIGHT, OF LOUISVILLE, KENTUCKY.

WRENCH.

1,243,506.

Specification of Letters Patent. Patented Oct. 16, 1917.

Application filed February 12, 1917. Serial No. 148,073.

To all whom it may concern:

Be it known that I, JOSIAH B. GATHRIGHT, a citizen of the United States, residing at Louisville, in the county of Jefferson and State of Kentucky, have invented certain new and useful Improvements in Wrenches, of which the following is a specification.

This invention relates to improvements in wrenches and consists in certain novel features of construction and correlations of parts substantially as hereinafter described and particularly pointed out in the claims.

The most important object of the invention is to provide a wrench of strong and durable construction which may be most economically manufactured.

This object, and others which will be apparent to those familiar with the present invention and the art to which it relates, is well accomplished by the construction illustrated in the accompanying drawings, which exemplifies an arrangement adapted to nuts, and in which drawings:

25 Fig. 1 is a side view of a wrench constructed in accordance with my invention;

Fig. 2 is a longitudinal section through the same;

Fig. 3 is an end view thereof;

30 Fig. 4 is a cross section on the line 4—4 of Fig. 2;

Fig. 5 is a detail view of the body portion, partially formed;

Fig. 6 is a view of said body portion completely formed;

Fig. 7 is a view similar to Fig. 6, but showing a body of slightly different cross-sectional shape; and

Fig. 8 is an end view of a wrench having 40 a body of the shape shown in Fig. 7.

Similar characters of reference denote corresponding parts in the several views.

Referring to the construction shown in Figs. 1-6, inclusive: A denotes the body portion of the wrench. This body portion is formed of a metal tube or pipe of suitable cross-sectional shape and size and at one end is slit longitudinally, as shown at a, Fig. 5, said longitudinal slit intersecting at 50 its rear end a transverse slit a'. The portions of the body lying between the transverse slit a' and the front end of the body and on opposite sides of the slit a are bent to form two upstanding substantially parallel spaced flanges 10, 11 which extend lon-

gitudinally of the body and are disposed at one end thereof.

B denotes the fixed jaw. The lower end 12 of this jaw has a cross section which conforms to the cross section of the body at the front end of the latter and substantially fills the same. Its intermediate portion 13 extends into and substantially fills the space between the flanges 10 and 11 at the front extremity of the body. This jaw thus closes 65 and stiffens one end of the body. It is rigidly secured to the latter in any approved way, as by the rivets 13^a for example.

The movable jaw is marked C. The cross-sectional shape of the lower and intermediate portions 14, 15 of this jaw conform to the cross-sectional shape of the portion of the body having the flanges 10 and 11 hereinbefore referred to, these portions of the jaw extending into the body and between 75 the flanges and being substantially in contact therewith, as shown in Fig. 4.

This jaw is threaded upon an adjusting shaft D which extends rotatably through a bearing block E and is suitably held against 80 longitudinal movement. The shaft D may have a threaded connection with the block E, or not, as desired. The latter being preferred, is shown in the drawings. In either case the block is held against movement longitudinally of the body. The bearing block E closes that end of the space between the flanges 10, 11 which is opposite the end closed by the intermediate portion 13 of the stationary jaw B. It is suitably 90 connected to the flanges 10, 11 as by the projecting pin 16, 16, for example. The shaft D has a head 17 which bears against the outer end of the block E and is, preferably, suitably roughened for convenience in 95 turning the threaded shaft D. Any suitable anchor may be provided to hold the shaft D against endwise movement with respect to block E. For example a pin 19 may be provided which passes through the fixed jaw B 100 and engages a groove 20 formed in the shaft D. It will be understood that when said shaft is turned in one direction or the other, the movable jaw C will be caused to advance toward or recede from the stationary jaw B to grasp or release a nut or the like and to accommodate nuts or the like of different sizes, and that in its movements it will be effectively guided by the flanges 10, 11.

It is preferred in practice to provide one or both of the upstanding flanges, 10, 11 with a scale, as shown at 18, Fig. 1, corresponding to different sizes of nuts or the like, for convenience in adjusting the movable jaw to engage the same by eliminating the necessity of guesswork in the preliminary adjustment of the jaw.

It is obvious that the body may be of various cross-sectional shapes, two of which are shown in the drawings: Thus, in Figs. 3, 5 and 6, I have shown a body which is cylindrical at the handle end and has its opposite end composed of a substantially cylindrical section flattened at the upper side where the upstanding flanges are located, and in Figs. 7 and 8 I have illustrated a body, marked A', which is substantially elliptical at the handle end and at its opposite end has its flattened portions, marked 10^a and 11^a in these figures, substantially in the vertical planes of the opposite sides of the handle portion. As the jaws conform to the shape of the parts of the body within which they are located, it will be apparent that the jaws for the first named form will be substantially cylindrical at their lower parts and flattened and of less thickness at their upper parts, as shown in connection with the jaws B and C in Figs. 3 and 4, while the jaws for the other exemplified form will be flat and of substantially the same thickness from top to bottom, as indicated in connection with the stationary jaw, marked B', in Fig. 8.

While I have illustrated, for exemplary purposes, the structure when embodied as a nut wrench, it will be apparent that the improvements constituting the present invention may be embodied as a pipe wrench, such embodiment involving merely certain changes in details well understood by those skilled in the art, and hence not illustrated herein.

Having thus described the invention, what

I believe to be new and desire to secure by Letters Patent, and what I therefore claim, is:

1. A wrench comprising a hollow body having integral upstanding spaced longitudinal flanges at one end, a stationary jaw secured between the flanges, a bearing block secured between the flanges at the inner ends thereof, a screw mounted to turn in the bearing block, and a movable jaw mounted to travel between the flanges, and to which jaw the screw is connected, and an operating member on said screw.

2. A wrench comprising a body portion formed of tubing which is split laterally and longitudinally adjacent one end and the split portions bent outwardly to form a pair of spaced flanges which extend outwardly beyond the body portion, a fixed jaw secured in position between the flanges at the outer end of the body portion, a bearing block secured between the flanges at the inner ends of said flanges, the fixed jaw and the bearing block serving to maintain the flanges in spaced relation to each other, a movable jaw guided between the outwardly extending flanges, an operating screw journaled in the bearing block and connected to the movable jaw, and an operating head on said screw rearwardly of the bearing block.

3. A wrench comprising a hollow body having integral upstanding, spaced, longitudinal flanges at one end, a stationary jaw fixed between the flanges at one end thereof, a movable jaw guided between the flanges, both the fixed and movable jaws extending outwardly beyond the flanges and inwardly into the body portion and conforming to the shape of the latter, a bearing block between the flanges at the rear ends of the latter, and a screw journaled in the bearing block and engaged with the movable jaw.

In testimony whereof I affix my signature.

JOSIAH B. GATHRIGHT.

Copies of this patent may be obtained for five cents each, by addressing the "Commissioner of Patents, Washington, D. C."
